UNITED STATES PATENT OFFICE.

MARK D. ROCHFORD, OF LOS ANGELES, CALIFORNIA.

METHOD OF DAM CONSTRUCTION.

SPECIFICATION forming part of Letters Patent No. 740,590, dated October 6, 1903.

Application filed August 15, 1902. Serial No. 119,808. (No model.)

To all whom it may concern:

Be it known that I, MARK D. ROCHFORD, a citizen of the United States, residing at Los Angeles, in the county of Los Angeles and State of California, have invented a new and useful Method of Dam Construction, of which the following is a specification.

In so-called "arid" districts or "semi-arid" districts there are rivers or streams which instead of being visible bodies of water flowing between banks comprise valleys with comparatively impervious bottoms on which are deposits of sand or pervious matter through which water percolates or works its way down and along to lower parts in seeking its level. The presence of the water in such valleys may not be apparent except in times of flood. Ordinarily the amount of deposits is so great and the water is so diffused throughout the body that the water is not visible from the surface.

One object of my invention is to provide a method whereby a dam may be constructed in the bed of such streams.

Another object of my invention is to provide a method whereby a dam of this character may be constructed in much less time than by any method heretofore known and at a considerable less expense than by any known method.

Another object is to provide a method whereby the dam may be constructed so that its bottom will conform to an irregular river-bottom and prevent water from working under the dam.

In the accompanying drawings, which illustrate one form of apparatus which may be used in carrying out my method, Figure I is a view showing a cross-section of a bed of a stream as before described. A part of the apparatus used is shown in elevation, and the dam is shown as having been completed across about half the stream. Fig. II is a side elevation of part of the apparatus. Fig. III is a front elevation of part of the apparatus. Fig. IV is an end view of casings which may be used in carrying out my method. Fig. V is a view illustrating the manner in which a casing may be removed. Fig. VI is a view showing a step in the method.

In carrying out my method I sink a casing vertically through the sand and water form-

ing the body portion of the stream, remove the sand or earth from within the casing, and then place within the casing a mass of impervious material. I repeat this operation next to the first casing, and after the second casing is filled I pull up the first casing and continue on across the stream, pulling up the casings as I proceed, but always leaving one casing to work against, which leaves a solid wall of impervious material, which extends across the stream, the bottom of the impervious material being in close contact with the bottom of the stream and conforming to every irregularity in the bottom of the stream.

The casings which are sunk may be of a suitable size and shape, so that they will withstand the external pressure of the sand and water when the material from within the casing is removed. I preferably employ a casing which is rectangular in cross-section, although in some cases it may be found preferable to employ a casing which is arched in cross-section or a casing which is substantially cylindrical in form.

A convenient way for sinking the casing into the stream is to force it down by hydraulic means. Fig. II shows a side elevation of an arrangement which is adapted for sinking a casing in that manner, in which 1 is a derrick having a tank 2 on the top thereof. 3 is a casing which is being forced in.

In the drawings I have shown and described a casing which is substantially rectangular in cross-section, although, as stated, under some conditions casings of other shapes may be found to be better adapted for the purpose.

I have spoken of the casings being rectangular in cross-section; but one side of the casing is open, and as the first casing is driven its open side is closed by means of plates 4, which I secure to the first casing as fast as the casing is sunk. It is not necessary to secure the plates to the other casings that follow, as the back wall of each casing serves the same purpose as the plates on the first casing.

Pressure may be applied to the upper end of the casing 3 through the medium of a plank 5, which is attached by suitable connections 6 to oppositely-arranged hydraulic jacks 7. The hydraulic jacks may be anchored, as at 8. Water may be forced into the hydraulic

jacks from a pump 9 through pipes 10. The driving down of the casing is facilitated by loosening up the sand and earth at the bottom of the interior of the casing, and this 5 may be accomplished by forcing water through pipes 11. One of these pipes may lie in each corner of the first casing and extend along the entire length of the casing, while the upper end of the pipes may be connected by means of hose 12 with the tank 2. The other casings may have only two of the 10 pipes 11. Water flows from the tank 2 through the pipes 11 and out at the bottom of the casing and stirs up the sand at the bottom, and 15 as water is constantly being supplied through the pipes the sand is forced up to the top of the bed and flows over the uppermost plate 4 onto the surface of the bed of the stream. The process of loosening the sand is further 20 facilitated by employing a flexible pipe 13, which may extend to the bottom of the casing and be carried over the top of the uppermost plate and be connected with a suitable pump 14. The water from the pump 14 is 25 discharged through the pipe 13 at the center of the bottom of the casing and further assists in the mixing up of the sand at the bottom of the casing and forcing the same out through the casing and onto the surface of 30 the stream. As the first casing is gradually sunk more plates 4 are secured, and the water is continually forcing the sand at the bottom of the casing to the top and over the uppermost plate onto the top of the bed of the 35 stream. As the casing is forced down the pipe 13 is lowered accordingly, so that its lower end will be kept near the bottom of the casing, the pipe 13 being of a length sufficient to allow of doing so. When the casing is 40 sunk so that the bottom of the casing rests upon the impervious material under the sand which forms the bottom of the bed of the stream, as shown in Fig. I, the downward progress of the casing is arrested; but water 45 is still pumped into the casing, and in a short time all of the sand or earth within the casing is removed and replaced by water, so that nothing remains within the casing but water. The pipe 13 may then be drawn out and the 50 interior of the casing filled with an impervious material—such, for instance, as clay or adobe. A convenient material in some localities would be adobe. After the casing has been entirely filled with the adobe to a suitable 55 height or to the height desired for the dam another casing may be placed in position and driven down in a similar manner next to the first casing and the sand or earth within the second casing removed in a similar manner and the casing then filled with impervious 60 material, and after the second casing is filled the first casing may be pulled out and used again and sunk next to the second casing, and so on across the bed of the stream 65 until the dam has been completed. I prefer, however, to leave the first casing in position and start in the middle of the stream and

work from both sides of the first casing toward the banks.

The casings may be pulled out, as shown 70 in Fig. V, by passing cables which are attached to the hydraulic jacks over sheaves 15, carried by the derrick, the ends of the cables being attached to the top of the sunken casing. It will be seen that the clay or adobe 75 will form a compact mass in the casing and being somewhat soft and plastic will conform to the irregular hard bottom of the stream, and a wall thus constructed will form an effective dam.

80 After removing a casing there may be a slight space formed between the adjacent columns of clay or adobe caused by the thickness of the wall of the casing; but the casing may be pulled up slowly, and the plastic material will close up the gap between the columns as fast as the casing is pulled up.

In order to insure that the columns will closely adhere and become merged, the pipe 13 may be left in position until the impervious 90 material has been placed within the casing, and while the casing is being removed plastic material—such, for instance, as mud—may be forced through the pipe 13 and into the interior of the impervious mass, which 95 will spread the mass and force it tightly against the adjacent column of impervious material, and after the casing has been removed the pipe 13 may be removed.

100 It may be desirable sometimes to employ a metallic or rigid pipe in place of the flexible pipe 13, the water being conducted to the top of the metallic pipe through a suitable hose from the pump 14, and after the casing is sunk the metallic pipe may be left in position, 105 and the clay or adobe may be placed around the pipe, and the pipe may be left permanently in the center of the column, so that if a small crevasse should occur between the adjacent columns or in the event of a leakage 110 occurring between the columns or underneath the columns a plastic material may be forced through the pipe, which would tend to spread the column of clay or adobe, and thus close the crevasse.

115 It is advantageous to provide the casings with lugs 16, which afford a means for engaging the inturned edges of the casings, as shown in Fig. IV, and serve to guide the casing being driven.

120 The apparatus which I have shown and described for carrying out my method is one which is well adapted for the purpose, although, as I have stated, the conditions under which the construction of the wall is to be 125 performed will largely determine the specific details required in carrying out the method.

130 In cases where concrete or cement is used as the impervious material in place of the adobe or clay the first casing may be removed after the second casing has been driven down, and while the first casing is being removed the second casing may be filled with the concrete as fast as the first casing rises, so that

the concrete which is being placed in the second casing will unite with the first mass or column of concrete. By this method there will be no gap formed between the adjacent columns, as there is no casing-wall to separate the columns.

Having described my invention, what I claim, and desire to secure by Letters Patent of the United States, is—

1. The method of dam construction consisting in forcing a casing into the bed of a stream, forcing another casing into the bed alongside the first casing, removing the sand or earth from within the casings, placing impervious material within the casings, and pulling up the casings.

2. The method of dam construction consisting of forcing casings into the bed of a stream in consecutive order, removing the sand or earth from within the casings, placing impervious material within the casings and withdrawing the casings.

3. The method of dam construction consisting in forcing a casing into the bed of a stream, removing the sand or earth from within the casing, placing impervious material within the casing, forcing a second casing into its bed alongside of the first casing, removing the sand or earth from within the casing, placing impervious material within the casing, forcing a third casing into the bed alongside the second casing, removing the sand or earth from within the casing, continuing the steps specified the required distance, pulling out the casings as the work proceeds but leaving the last casing in until the new casing is sunk, and so on, so that each new casing is guided by the preceding sunken casing.

4. The method of dam construction consisting in forcing casings into the bed of a stream in consecutive order and as each casing is put in simultaneously forcing water into the interior of the casing and dislodging and removing the earth from within the casing, and subsequently filling the casings with impervious material, and ultimately withdrawing the casings.

5. The method of dam construction consisting in forcing casings into the bed of a stream one after another, and as each casing is sunk simultaneously directing a stream of water approximately through the center of the casing and also directing streams of water along the walls of the casing and removing the earth from within the casing, subsequently filling the casing with impervious material and ultimately withdrawing the casings.

6. The method of dam construction consisting of forcing a casing into the bed of a stream, removing the sand or earth from within the casing, placing a pipe in the center of the casing, placing impervious material within the casing externally of the pipe, then withdrawing the casing, then gradually withdrawing the pipe and simultaneously forcing through the pipe a plastic material and spreading the impervious mass.

In witness whereof I have signed my name to this specification, in the presence of two subscribing witnesses, at Los Angeles, in the county of Los Angeles and State of California, this 9th day of August, 1902.

MARK D. ROCHFORD.
